UNITED STATES PATENT OFFICE.

FREDERICK M. TURCK, OF NEW YORK, N. Y., ASSIGNOR, BY MESNE ASSIGNMENTS, OF ONE-HALF TO MABEL TRACY, OF SAME PLACE.

MANIFOLD SALES-BOOK.

SPECIFICATION forming part of Letters Patent No. 662,043, dated November 20, 1900.

Application filed March 15, 1899. Serial No. 709,157. (No model.)

To all whom it may concern:

Be it known that I, FREDERICK M. TURCK, a citizen of the United States, and a resident of New York, in the county of New York and 5 State of New York, have invented certain new and useful Improvements in Manifold Sales-Books, of which the following is a specification.

My invention has reference to improvements in manifold sales-books used principally by salesmen in commercial establishments by which duplicate or triplicate copies can be made with one writing. In the triplicate books of this class heretofore used the 15 three copies are made in one piece with perforations for the purpose of separation, and the sheets are bound together, fifty leaves in one book, and after the writing has been done all three copies are torn from the book or 20 else two only are removed and one remains in the book as a stub. In my book two of the triplicate copies are from a loose leaf, and the other copy appears in a bound book, which I will designate a "record-book," consisting 25 of twenty-five leaves, the book being reversible, utilizing both sides of the paper, thus taking but half the paper usually required. For duplicates the record-book is dispensed with and only loose leaves are used, thus saving 30 the expense of binding and folding.

The features of my invention are illustrated in the annexed drawings and fully pointed out in the following specification and in the claims.

35 In the accompanying drawings, Figure 1 is a perspective view of my improved manifold book, showing the arrangement of the impression and carbon sheets preparatory to obtaining a triplicate print. Fig. 2 is a perspective view of the same preparatory to obtaining duplicate prints. Fig. 3 represents a view of the book, showing the manner in which the record-book is attached and the loose sheets are stored, while in Fig. 4 the cover, 40 with the loose-sheet carrier, is shown, the record-book and loose sheets being removed. Figs. 5 and 7 are respectively a front and a rear view of the loose-sheet carrier. Figs. 6 and 45 8 are a top and a bottom view, respectively, 50 of the same; and Fig. 9 is a face view of a tally-sheet used in combination with my im-

proved memorandum-book. Fig. 10 is a detached perspective of the carrier B of the loose sheets. Fig. 11 is an inverted view of the retaining-frame for the loose sheets. Fig. 12 is a longitudinal vertical section taken through the left-hand cover and its attachments. Fig. 13 is a vertical section taken through the book upon the dotted line 3 3 of Fig. 12. 55

A represents the covers of the book, made of card-board or any other suitable material and covered in the same manner as the covers of ordinary books, and the two covers are united by the usual flexible back A'. The outer edge 60 of the left-hand cover is provided with a sheet-metal binding g², (shown more especially in Fig. 3,) and connected to this binding is the elastic pin g, which has its free end to engage with the hook g' after the sheets of 65 paper D have been applied thereto. These sheets of paper D are bent double at their centers and the pin g is passed through them at their doubled portions for the purpose of attaching the sheets loosely to the cover. 70 These sheets D form a record-book and when filled upon one side are reversed, so that they can be filled upon the other, and thus save one-half the amount of paper usually necessary. 75

Loosely attached to the back A' or to the 80 inner edge of the left-hand cover by means of the flexible material b' is the carrier B for the left-hand pile of sheets H, and which carrier consists of a piece of pasteboard or other suitable material which forms a support upon 85 which one-half of the sheets H are supported. If so desired, this carrier may be covered by means of a plate of sheet metal b², which covers the right-hand side of the carrier, and which sheet of metal has its ends turned 90 over upon the carrier B at opposite edges. When this plate or cover b² is used, the loops c will be formed as an integral part thereof, as shown more especially in Figs. 4 and 10. The inner upper corner of this plate b² is 95 turned upward at right angles and at a suitable inclination, as shown in Fig. 10, so as to form a stop to prevent the ready removal of the sheets H, and the corner e' of this upturned corner x is bent over at right angles to the portion x, so as to catch over the top of the frame and prevent it from rising. At the opposite corner 100

of the plate b^2 is formed the loop e , which is turned at right angles to the plate b^2 and which serves as a guide for the wire d . As shown in Fig. 10, this plate b^2 is perfectly flat upon its top, with the exception of the corner x and loop e , and serves simply as a support for the left-hand half of the leaves H . These leaves H are bent at their centers, as indicated in Figs. 1 and 2, and are intended to be separated along the central lines. In order to adapt these leaves to be applied to the support B , their upper edges have a V-shaped notch made therein, as shown in Figs. 1 and 2, so as to catch under the turned-up corner x , which prevents them from having a lateral movement upon the carrier B , and these leaves are prevented from having an endwise movement not only by the turned-up corner, but by the loop e . As it is necessary to hold down the leaves placed upon the carrier B , so as to prevent them from becoming readily displaced, a retaining-frame C (shown more especially in Fig. 11) is used, and this frame, which extends around on three sides only, is attached to the support B by means of the wire d . This wire d passes through the loops c on the plate b^2 , and, as shown in Fig. 11, it then extends along the inner sides of the frame C nearly to its outer edge, where the wires are passed through the edges of the frame and fastened by bending back or in any other suitable manner. This wire not being attached to the retaining-frame at its inner end allows the frame C a slight vertical movement, so as to adapt itself to the thickness of the leaves H placed upon it. The upper and lower edges of this frame C are turned downward at right angles, so as to catch over the edges of the leaves H upon the carrier B , and to the outer edge of the frame is attached the pivoted clasp f , which catches over the edge of the carbon and waxed papers and secures them in position. In order to prevent the outer edge of this retaining-frame C from moving away from the outer edge of the carrier B more than just enough to allow the sheets H to be inserted between the frame and the carrier B , the flexible retaining-strips d^2 are used, and which are fastened to the outer edges of the support B and to the outer edge of the retaining-frame C , and thus the retaining-frame can never move away from the carrier B more than just sufficient to allow the sheets H to be inserted. The frame C being held at its inner edge by the wire d and at its outer edge by the retaining-bands d^2 , it moves with the carrier B as though formed a part thereof. The clamping-rod f serves to hold the carbon-sheet in position ready for use. This sheet i extends the full length of the loose leaves and is carboned on both sides. On top of the carbon-sheet, and also held by the clamp f , is a sheet of waxed or other paper k , extending only half over the loose leaves, and which waxed sheet prevents the under side of the record-leaf from being marked or soiled when writing.

In books to be used only for duplicate impression the attachment for the record-book is dispensed with, as shown in Fig. 2. The right-hand-side cover is provided with a pocket h , in which is tucked a summary or tally-sheet for entries referring to the sales, or any other entries may be made. This record-sheet projects with one half out of the pocket, while the other half is hidden therein and will be reversed after that first half is used up. This is attained by providing the two halves with entry scales or prints in opposite directions, as shown in Fig. 9.

When the book is to be used, the record-book is attached thereto by means of the retaining-wire g , while the loose sheets having the triangular cut or other retaining-notch mentioned above in the upper middle portion are stored on the sheet-carrier B and retained thereon by the overlapping flaps d' and the diagonal guide-hook X of the carrier B , the flaps d' serving to prevent an upward and the diagonal guide-hook a lateral removal of the sheets from the sheet-carrier. The carbon-sheet i and the wax-paper sheet k are kept in place by the clamping-rod f , the carbon-sheet covering the entire length of the loose sheets, and the wax-paper sheet extending half-way or to the line of perforation of the loose sheets which are retained by the retaining-frame.

The use of my improved manifold-book is very simple. To produce triplicate impressions, Fig. 1, the under sheet of the record-book is placed upon the wax-paper sheet, and then the fore half of the carbon-sheet and the top sheet of the loose sheets are folded back on themselves on the line of the perforation on the loose sheet, so that the said sheet of the record-book is covered by the same. When the writing has been done, three copies are obtained—two on the loose leaf (by pencil and carbon-sheet) and one by carbon on the sheet of the record-book. After removal of the loose leaf the loose-sheet carrier is raised and swung on its hinge sufficiently far to straighten the carbon at its full length, when at the same time the written-on sheet of the record-book will fall underneath the sheet-carrier and be stored as finished business. When the leaves of the record-book have all been used on one side, the book is reversed, so as to use the other side of the paper, both sides of the book being written on. It is evident that for obtaining only two impressions the record-book is dispensed with, and a carbon-sheet is required, reaching only half-way of the sheet and to line of perforation.

My improved manifold memorandum-book is very simple and cheap in its manufacture, as no springs and complicated implements are used, and it requires less paper and no folding nor binding in the duplicate form. The record-book is easily removable and the loose sheets are reliably kept in place by the simple construction of the sheet-holder which

holds one-half of the impression-sheets in reliable storage and yet admits an easy removal of the single sheets and allows the other free halves of the sheets to be folded over the in- 5 closed halves, so that when the book is closed the memorandum-pad, as well as the carbon-sheet and the impression-sheets, is entirely inclosed by the covers.

By means of the construction here shown 10 a springless collapsible sheet-holder is placed within the covers of a book, and said sheet-holder holds that portion of the flat unfolded pile of leaves extending from the notch in the pile of sheets to one extremity thereof.

15 Having thus described my invention, I claim as new and desire to secure by Letters Patent—

1. In a manifold memorandum-book, the covers, the record-sheets D, means for holding 20 the record-sheets at the outer edge of one of the covers, the loose sheets, and a carrier for holding the loose sheets, and which carrier is hinged at one side to the cover of the book, combined with a retaining-frame attached to 25 the carrier for holding the carbon and waxed paper, one-half of the loose leaves being loosely held between the carrier and the retaining-frame; said carrier and retaining-frame forming a collapsible holder for the 30 loose sheets, substantially as shown.

2. In a manifold memorandum-book, the covers, a springless collapsible sheet-holder placed within the covers of a book and consisting of the flat carrier B, an upturned projection x, and the retaining-frame C, combined with the loose sheets placed between the carrier and the retaining-frame, substantially as described.

3. In a manifold sales-book, the covers, the 40 loose sheets, the carrier B for the loose sheets hinged to the cover, an upturned projection for catching in a notch in the edges of the loose leaves, combined with a three-sided retaining-frame loosely connected to the carrier, and which catches over the top of one-half of the leaves, substantially as set forth.

4. In a manifold sales-book, the cover, a flat carrier hinged to the cover and upon which the loose leaves are placed, combined with a 50 three-sided retaining-frame provided with flanges upon two of its edges for catching over the edges of the leaves, a projection at the upper corner of the flat carrier, and means for connecting the retaining-frame to the carrier at their edges, said means permitting a free rising and falling movement of the re-

taining-frame so as to accommodate itself to the thickness of the pile of loose leaves, substantially as specified.

5. In a manifold sales-book, the cover, and 60 a carrier for the loose sheets, which carrier is hinged to the cover, and a three-sided retaining-frame, combined with a wire which is connected at the inner edge of the carrier B at the center of the wire, and which wire has 65 its outer ends connected to the retaining-frame, flexible retaining-strips which connect the outer edges of the carrier and the retaining-frame, so as to allow the retaining-frame a slight upward movement in relation 70 to the carrier, and means connected to the carrier for limiting the upward movement of the retaining-frame at its inner corners, substantially as specified.

6. In a manifold sales-book, a cover, a carrier for the loose sheets provided with the upturned corner x and the loop e; and the wire d which is connected to the inner edge of the carrier by means of the loops c, combined with the three-sided retaining-frame to which 80 the outer ends of the wire d are fastened, a clamping device attached to the outer edge of the retaining-frame and the bands d² which connect the outer edges of the retaining-frame and the outer edges of the carrier, substantially as specified. 85

7. In a manifold sales-book, the cover, the pin g connected to the outer edge of one of the covers to receive the record-sheets, and the carrier loosely connected to the cover at 90 or near its center and provided with the loops c, at its inside edge, and the loop at its lower edge, and the upturned corner x provided with the projections e', combined with the three-sided retaining-frame, the wire by 95 means of which the frame is loosely connected to the carrier; the retaining-bands d² for connecting the outer edges of the carrier and the retaining-frame, the clamp f, and the loose sheets H provided with a notch in 100 one of their edges, one-half of the sheets being held between the carrier and the retaining-frame, substantially as shown and described.

Signed at New York, in the county of New 105 York and State of New York, this 14th day of March, A. D. 1899.
